UNITED STATES PATENT OFFICE.

WILLIAM B. FENN, OF WINFIELD, NEW YORK, ASSIGNOR TO EZRA D. BECKWITH, OF SAME PLACE.

DESIGN FOR A WATER-BOTTLE.

SPECIFICATION forming part of Design No. 32,427, dated April 3, 1900.

Application filed March 7, 1900. Serial No. 7,728. Term of patent 3½ years.

To all whom it may concern:

Be it known that I, WILLIAM B. FENN, a citizen of the United States, residing at West Winfield, in the county of Herkimer and State of New York, have invented and produced a new and original Design for Water-Bottles; and I do hereby declare the following to be a full, clear, and exact description of the same, reference being had to the accompanying drawing, forming part thereof, and in which the figure is a side elevation of a water-bottle embodying my design.

10 A represents the body or base of the bottle and which is substantially bell or dome shaped, as shown.

15 B represents the neck of the bottle, which extends vertically from the upper portion of the base of the bottle, said neck having a lower flaring surface B'.

20 C represents a ring which has an upper

curved surface C', joining the said flaring surface of the neck, and a lower vertical surface C², which joins the upper surface of the bell or dome shaped base.

The essential features of my design consist 25 in the bell or dome shaped base, the vertical neck extending from the upper central portion of the base, said neck having a lower outwardly-flaring portion, and a ring having an upper inwardly-directed portion which 30 joins the said flaring portion and lower downwardly-directed portion which joins the upper portion of the base.

I claim as my invention—

The design for a bottle, substantially as 35 herein shown and described.

WILLIAM B. FENN.
